Marks. Aukerman
ATTORNEY

UNITED STATES PATENT OFFICE.

JOHN KOWALSKI, OF GLEN LYON, PENNSYLVANIA.

SHOE-POLISHING KIT.

Application filed April 19, 1926. Serial No. 103,016.

This invention relates to shoe polishing kits, and has for an object the provision of a holder for the polish container, associated with a foot support that may be applied 5 to a stand, chair, bench, or the like, in order that the device can be used without liability of scratching the furniture or daubing the same as the polish is applied and treated.

It is an object of this invention to provide 10 a holder for the polish container and a shoe supporting pad connected to the holder at its edge, and preferably to provide a beveled surface between the holder and the pad where the toe of a shoe being polished may 15 rest, whereas the sole of the shoe may rest on the pad.

It is furthermore an object of this invention to provide a holder having a lid to cover the polish container and to provide 20 means for retaining the polish container in the holder, the said device being of comparatively inexpensive construction, as well as efficient and satisfactory in use.

With the foregoing and other objects in 25 view, the invention consists in the details of construction, and in the arrangement and combination of parts to be hereinafter more fully set forth and claimed.

In describing the invention in detail, reference will be had to the accompanying 30 drawings forming part of this application wherein like characters denote corresponding parts in the several views and in which—

Figure 1 illustrates a plan view of a device embodying the invention;

Figure 2 illustrates a sectional view on the line 2—2 of Fig. 1; and

Figure 3 illustrates a view in side elevation.

In these drawings, 5 denotes the body of the holder for the polish container, the said holder having a cavity or well 6 in which the container is deposited. Preferably a 45 screw 7 is threaded through one wall of the holder and carries a clamp 8 which will partially embrace the container and bind it against the wall of the well or cavity, where it will be held against accidental displacement when implements are being used to remove the contents of the container. A lid 9

is preferably hinged to the end of the holder and it has a plate 10 preferably of rubber, which will serve to close the container and prevent evaporation of the contents thereof. 55 The lid or cover will be held closed by any suitable latch such as 11, although the inventor does not wish to be limited with respect to the particular form of latch employed.

One end or edge of the holder is beveled, as shown at 12, in order that the toe of the shoe may rest partially on the holder, and this beveled portion has a curved recess which may conform to a great extent to the 60 contour of the end of a sole of a shoe.

A pad 13 of relatively heavy flexible material has an end anchored to the holder under the beveled end thereof, and this pad is of the general conformation of the sole of 70 a shoe, although larger than normal shoes in order that there will be considerable area available for use when the shoe is placed on the pad for polishing.

The outer end 14 of the pad may be 75 flanged or bent over, and this portion has two sets of connected slits 15 and 16 forming in the pad, tongues that will be displaced upon the insertion of a brush handle through the slits to temporarily secure such 80 brush to the pad, when not in use.

I claim:

1. In a shoe polishing kit adapted to be supported on a chair or step, including a body portion forming a polish holder, a pad 85 attached to the body at one edge, the said edge being beveled to merge with the upper surface of the pad, and the outer end of said pad being adapted to be flexed downwardly over the edge of the chair or step by 90 the heel of a shoe resting on the pad, to thereby hold the kit from slipping.

2. In a shoe polishing kit, a holder for a polish container, a shoe supporting pad secured to the holder at one edge thereof, the 95 said holder being beveled along said edge to merge with the upper surface of the pad, the beveled portion having a recess formed therein, to accommodate the tip of a shoe resting on said pad.

JOHN KOWALSKI.
